United States Patent Office.

JOHN PALEY AND THOMAS RAWSTHORNE, OF PRESTON, GREAT BRITAIN.

Letters Patent No. 74,585, dated February 18, 1868; patented in England, November 23, 1864.

IMPROVEMENT IN MULES FOR SPINNING.

The Schedule referred to in these Letters Patent and making part of the same.

TO ALL WHOM IT MAY CONCERN:

Be it known that we, JOHN PALEY, of Preston, cotton-spinner, and THOMAS RAWSTHORNE, of Preston, manager, both in the county of Lancaster, and Kingdom of Great Britain, have invented an Improved Method of Driving the Cam-Shaft of Self-Acting Spinning-Mules; and we do hereby declare that the following is a full and exact description thereof, which will enable those skilled in the art to make and use the same, reference being had to the accompanying drawing, and to the letters of reference marked thereon.

This invention relates to a means for driving the cam-shaft of self-acting mules. The motion of the cam-shaft is now commonly obtained from the driving-shaft, by means of friction-pulleys, which frequently fail in action, and thus lead to frequent breakages of the machinery. By our invention, the cam-shaft is operated through a belt from an overhead or any convenient shaft, and a fast and loose pulley on the said cam-shaft, or by an obvious modification, the fast and loose pulley can be placed on a counter-shaft, mounted in any convenient position, and geared into the cam-shaft by wheels. In this example of our invention we have shown a fast and loose pulley on the cam-shaft, which are worked by a band from an overhead-shaft, on which is fixed a pulley for the purpose of driving. This band may be moved from the fast to the loose pulley, and *vice versa*, by a crank-lever, acted upon by the travelling-frame of the mule at each end of its traverse.

To enable others skilled in the art to make and use our invention, we will proceed to describe its construction and operation.

The drawing, consisting of only one figure, is a side elevation of a portion of the frame of a self-acting mule, showing a portion of the cam-shaft and of the overhead-shaft.

The letter *a* designates the driving-shaft, from which we propose to obtain our motion for the cam-shaft, which is seen below it, mounted in bearings on the frame. We fix upon the said shaft *a* the driving-pulley *c*, from which a band, *b*, goes to the fast and loose pulleys *d d*, that are provided on the cam-shaft. The band *b* is removed from the fast to the loose pulley, and *vice versa*, by the fork-lever *h*, which is connected to the vertical arm of an elbow-lever, *i*, pivoted on the frame, as shown in the drawing. The said lever *i* is connected by a horizontal rod, *f*, to a pendent lever, *e*, on whose lower end is a pin, *k*, which is acted upon by the travelling-frame of the mule at its extreme motion out. On the side of the travelling-frame, inside, is a pin, *j*, which, at the extreme inner motion of the frame, slides along beneath the taper block or cam, which is attached to the horizontal arm of lever *i*, and lifts the same, and thereby gives motion to fork *h*, so as to move the band *b* from the loose to the fast pulley. The extreme end of the horizontal part of lever *i* is weighted, as seen at *m*, the office of the weight being, on the return of the travelling-frame, to turn the lever *i* and draw the band *b* from the fast to the loose pulley, thereby stopping the motion of the cam-shaft when required.

We do not confine ourselves to this particular device for removing the band *b*, as we can and may effect the same object by other means, which will suggest themselves to the intelligent mechanic, nor do we confine ourselves to the precise details or arrangements which we have above described, as many variations may be made therefrom without deviating from the principle of our invention.

Our invention effects a great saving of wear and breakage, besides being almost noiseless in action, and enabling the necessary changes of the cam-shaft to be made at any required speed without danger of breakage.

What we claim as new, and desire to secure by Letters Patent, is—

The combination, with the driving-band *b*, of the fast and loose pulleys *d* of the cam-shaft, the connected levers *e i*, and the block *l* and weight *m* of lever *i*, substantially as shown.

JOHN PALEY, [L. S.]

THOMAS RAWSTHORNE. [L. S.]
